(57) **CLAIM**

The ornamental design for a universal handle and accessory head for fascia tissue treatments, as shown and described.

DESCRIPTION

FIG. 1 is a front perspective view of a universal handle and accessory head for fascia tissue treatments;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top view thereof; and,

FIG. 7 is a bottom view thereof.

The broken lines shown as dashed lines are for the purpose of illustrating unclaimed structure, and form no part of the claimed design.

1 Claim, 4 Drawing Sheets
